UNITED STATES PATENT OFFICE.

EDGAR T. LANCASTER, OF PALATKA, FLORIDA.

APPARATUS FOR REMOVING WALL PAPER.

Application filed February 17, 1921. Serial No. 445,722.

To all whom it may concern:

Be it known that EDGAR T. LANCASTER, a citizen of the United States, residing at 601 Lemon Street, Palatka, in the county of 5 Putnam, State of Florida, has invented certain new and useful Improvements in Apparatus for Removing Wall Paper, of which the following is a specification.

My invention relates to an apparatus for 10 removing old wall paper from the wall, and consists mainly in the applying of live saturated steam directly onto the face of the wall paper, thereby destroying the adhesive properties of the paste between the 15 paper and the wall, thus causing the paper to become loosened or disengaged so that it may be easily removed.

The main and particular objects and advantages of my invention, are to provide 20 an efficient, sanitary, and comparatively inexpensive apparatus for removing wall paper. A further object is to make the apparatus safe to handle and use, and so simple in operation and construction, that 25 but little skill will be required in operating it. Another advantage found in the use of this apparatus is, that all insect vermin on the walls or in crevices and cracks in and around the walls are destroyed, together 30 with their eggs and larva, by exposure to the live steam.

These and other objects and advantages 35 will be clearly understood from the following specification and drawing of various preferred models of the apparatus, although modifications might be made in these without departing from the scope of my invention.

Fig. 1 is a front elevation of a preferred 40 model of a portable apparatus.

Fig. 2 is a plan view of an apparatus for attaching to some available source of steam.

Fig. 3 is a side elevation of Fig. 2.

Figs. 4, 5 and 6 are various modifications 45 of steam spray nozzles for use with the apparatus.

Referring to the several views at the same time, Fig. 1 consists of a portable steam boiler 1 in which the steam is generated, the 50 water in the boiler is heated by a burner 2 located under the boiler. An opening 3 is formed in the boiler shell, which extends downward some distance below the boiler proper, which is indicated by the dotted 55 line 4, so as to form a space in which the burner may be placed. A bottom 5 is riveted

to the extended boiler shell and feet 6 are secured on this bottom plate. The burner 2 is held securely in place by spring snaps 7, which are riveted to the bottom plate 5. 60 Near the top or dome 8 of the boiler a steam outlet 9 and a steam valve 10 are placed. To this valve a flexible hose or tube 11 is attached, the other end of this tubing, which may be of any required length, is 65 attached to a pipe 12 which passes through a heat insulating handle 13. At the outer end of the handle 13 a steam valve 14 is fastened on pipe 12. The valve 14 is of the spring type, and has a lever 15 which when 70 depressed opens the valve, while normally the valve is closed.

To the other end of the valve 14 another flexible hose or tube 16 is attached, which connects with a steam spray nozzle 17. This 75 nozzle 17 is pivotally held between the pivots 18 riveted in the two flexible steel arms 19 which are themselves secured to the handle 13, as shown at 20. As the arms 19 are flexible they may be spread apart so that 80 the steam spray nozzles 17 may be removed and other nozzles substituted. The various nozzles have conical depressions 21 into which the pivot points 18 enter.

The steam spray nozzles have at each 85 end flanges 22 which have flat sides 23. These flat sides are plainly shown in Fig. 1, where they are shown placed against the wall 24. They are also plainly shown in Fig. 3. Centrally between these flat sides 90 or faces 23 are located the openings or orifices 31 through which the steam is sprayed. In Fig. 2 the orifice 31 is shown as a narrow slot extending the whole length of the nozzle. In Fig. 5 the orifices 31 consist 95 of a row of small circular holes, while in Fig. 6 the orifices are narrow slots cut cross-wise with the length of the nozzle. The reason for the different orifices is to provide for the difference in texture and thickness 100 of the paper to be removed, each shape being particularly adapted for certain uses. In Fig. 4 is shown a nozzle for use in corners, the orifice 31 here shown consists of a long narrow slot, but any other style of orifice 105 may be used.

Referring again to Fig. 1 the boiler 1 is provided with a steam gauge 25, a safety valve 26 which also acts as a means for filling the boiler with water, a water gauge 27 110 and a handle 28 by which the apparatus may be carried. 29 are ventilating openings for

the burner. Fig. 2 and Fig. 3 only differ from the similar parts on Fig. 1 by having a union or other suitable coupling 30 at the end of the flexible tube 11. The coupling 5 30 is used for connecting the flexible tube with a steam radiator or other suitable source of steam supply, where such is found in the room or building where the work is to be performed, thus eliminating the use of the 10 portable boiler.

The operation and use of the apparatus is as follows:—The portable boiler is partly 15 filled with water and the burner lit so as to generate the necessary steam. While the steam is generating the operator selects the suitable steam spray nozzle 17 and by spreading the flexible arms 19 apart inserts the nozzle between the pivots 18 so that these will engage in the conical depressions 20 21 in the flanges 22. He then attaches the hose 16 to the nozzle. The apparatus is now ready for work as soon as sufficient steam has been generated in the boiler.

The operator grasps the handle 13 and 25 by depressing the valve lever 15 with the thumb, opens valve 14, thus allowing the free passage of steam from the boiler to the nozzle, he next places the flat sides 23 on flanges 22 against the wall 24 near the ceiling and slowly moves the nozzle downward toward the floor. The valve 14 being held open steam will issue from the nozzle and cause the paper to become loosened from the wall. The nozzle 17 is preferably made 35 somewhat wider than the strips of paper so that one strip may be loosened at a time.

The valve 14 is now closed and the strip of paper removed, the process is then repeated on the next strip, until all the paper 40 is removed. If it is now desired, the operator may again go over the wall with the nozzle and by forcing the steam into all crevices and openings in and around the

wall, destroy any insect vermin which may be found there. It will be noted that during the sliding of the nozzle 17 up or down the wall the flat sides 23 will always be guided against the wall and so cause the sprays of steam, which issue from the orifices 31, to be directed toward the wall. This is made possible by the way the nozzle 17 is held between the pivots 18 and by the flexible tube 16. As previously explained, the boiler may be dispensed with and the coupling 30 connected to a steam outlet, when such is available in the room or building where the work is done.

I claim:

In an apparatus for removing wall paper; a portable steam boiler, having a steam outlet near its top; a main valve attached to said outlet; a flexible hose connecting said main valve with one end of an operating handle; the operating handle, consisting of a pipe incased in a heat insulating covering, forming part of the steam conduit; a spring operated valve attached to the other end of the operating handle; a flexible hose connecting said spring operated valve with the inlet pipe of a steam spray nozzle; the steam spray nozzle consisting of a perforated tube, having guide flanges at both ends; sockets formed in said guide flanges; flexible arms, secured on the operating handle, extending outwardly and forwardly, and having pins 75 secured at their outer ends; and said pins engaging in the sockets in the steam spray nozzle flanges.

In testimony whereof, EDGAR T. LANCASTER has signed his name to this specification 80 in the presence of two subscribing witnesses, this 14th day of February, 1921.

EDGAR T. LANCASTER.
